UNITED STATES PATENT OFFICE.

PERCY R. DRENNING, OF BALTIMORE, MARYLAND, ASSIGNOR, BY MESNE ASSIGNMENTS, TO THE SYMINGTON COMPANY, A CORPORATION OF MARYLAND.

JOURNAL BOX.

Application filed April 5, 1924. Serial No. 704,357.

The invention relates to journal boxes for use on railway vehicles and more especially involves an improved construction of hinged lid and spring means for maintaining the 5 same in both open and closed positions.

One of the objects of the invention is to provide a one-piece lid having associated therewith a torsion spring floatingly supported by a member movably connected to the 10 lid, said spring having an extending portion cooperating with the means pivotally connecting the lid to the journal box and also having another extending portion adapted to bear against a projecting portion of the lug 15 to which the lid is hinged.

A further object of the invention is to produce a comparatively simple, strong and durable journal box lid, the parts of which can be easily manufactured and readily assembled 20 whereby they will effectively operate to maintain the lid firmly seated against the journal box while also permitting longevity of use in the repeated lifting of the lid incident to service conditions.

25 The invention further consists in the combination, arrangement and construction of the several parts hereinafter described and pointed out in the claims.

In the drawings chosen to illustrate the invention, wherein similar reference characters 30 designate corresponding parts in the several views:

Figure 1 is a fragmentary view in elevation of a journal box constructed in accordance 35 with the present invention, a portion of the lid thereof being shown broken away.

Figure 2 is a vertical sectional view through the lid and adjacent portion of the journal box to which it is hinged, said view 40 being taken on the line 2—2 of Figure 1.

Figure 3 is a detail sectional view through the coil or helix portion of the torsion spring illustrating a modified construction of supporting means for said spring extending 45 directly from the lid.

Figure 4 is a detail horizontal sectional view of a portion of the spring and lid shown in Figure 3, the retaining means for said spring being shown in bent position in full 50 lines for supporting the spring and in initial or unbent position in dotted lines.

According to the present invention the lid 1 is preferably formed with a central portion offset to provide a pocket or interior for receiving the double coils or helixes of the tor-

sion spring together with the associated lever member, all as will presently appear. The upper end of the lid is provided with spaced portions providing the sleeves 2 through which passes the pintle 3 hinging the lid to 60 the journal box. The journal box is provided with a lug 4 through which the pintle extends, said lug having cam faces 5 and 6, respectively, with which an extending portion of the torsion spring cooperates in maintaining 65 the lid in closed and open positions.

The torsion spring 7 is formed of spaced helixes 8, the portion of the spring intermediate said helixes being formed into a looped extension 9 adapted to cooperate with the respective cams 5 and 6. A wear plate 10 is preferably clipped to the upper portion of the looped extension by means of the bent tongues 11. The ends of the torsion spring are relatively long and curved inwardly toward the 70 plane in which the looped extension lies, said ends being curved or hooked at their outer extremities and designed to bear against the pintle 3.

Cooperating with the spring is an arm or 75 member 12 interposed between the helixes thereof, said arm having portions 13 projecting into said helixes and providing supports, bearings or pivots for the spring. The lower end of the arm is reduced and received into an opening 14 formed in an integral inwardly 80 projecting portion 15 of the lid, said arm contacting one wall bordering said opening and acting through the spring to maintain the lid in firmly seated position against the journal box, as clearly shown in Figure 2.

The upper end of the arm 12 is provided with a shoe portion 16 transversely disposed so as to bridge the looped portion of the spring and bear against the upwardly extending portions at a point intermediate the helixes of the spring and the upper end thereof 95 cooperating with the cam surfaces on the lug 4. The arm or member 12 acts in the nature of a lever floatingly connecting the spring to the lid and operates, through its sliding contact with said lid and firm engagement with said spring, to maintain the former in open and closed positions, as occasions 100 require.

In Figures 3 and 4 a modified construction is shown in which the helixes of the torsion spring are effectively connected to the lid by means of bendable portions or tangs 17 preferably formed integral with the lid. The 110

ends of the tangs 17 are preferably shaped to conform to the circular contour of the coils or helixes of the spring and provide a convenient and simple means for connecting the spring to the lid.

I claim:

1. The combination with a journal box, of a lid, means hinging said lid to the journal box, means including a lug on the journal box for maintaining the lid in a plurality of positions, said lug having a plurality of faces, a torsion spring provided with an extending portion adapted to coact with said faces, and another portion coacting with the means hinging the lid to the journal box, and means connecting said spring to the inside of the lid.
2. The combination with a journal box, of a lid, a pin hinging said lid to the journal box, means including a lug having a plurality of faces for maintaining the lid in a plurality of positions, a torsion spring provided with an extension adapted to coact with said faces and another extension designed to coact with said pin, and means connecting the spring to said lid and normally covered thereby.
3. The combination with a journal box, of a lid, means hinging said lid to the journal box, means including a lug on the journal box for maintaining the lid in a plurality of positions, said lug having a plurality of faces, a torsion spring provided with an extending portion adapted to coact with said faces and another portion coacting with the means hinging the lid to the journal box, and a member having a portion supporting the helix of said torsion spring, said member having a portion adapted to bear on the extension of the spring coacting with the faces on said lug, said member also having another portion connecting the spring to the lid.
4. A journal box comprising a one-piece lid, means hinging said lid to the journal box, a lug on the journal box having a plurality of faces serving to maintain the lid in a plurality of positions, a torsion spring having spaced helixes and an intermediate loop portion adapted to coact with said faces, the opposite ends of said helixes being extended for coaction with the means hinging the lid to the journal box, and means detachably connected with the lid and engaging said helixes for supporting the spring, said means having a portion contacting the intermediate loop of said spring.
5. A journal box comprising a lid, means hinging said lid to the journal box, a lug on the journal box having a plurality of faces serving to maintain the lid in a plurality of positions, a torsion spring provided with an extension coacting with said faces and another extension coacting with the means hinging said lid to the journal box, and a

lever member connecting the spring to the lid, said member having oppositely extending portions one of which is movably connected to the lid and the other of which is adapted to bear upon the extending portion 70 of the spring coacting with the faces on said lug.

6. A journal box comprising a lid, means hinging said lid to the journal box, a lug on the journal box having a plurality of faces 75 serving to maintain the lid in a plurality of positions, a torsion spring provided with an extension from a torsion portion thereof coacting with said faces and another extension coacting with the means hinging said lid to the journal box, and a member connecting said springs to the lid, said member having a projection adapted to bear upon the extending portion of the spring between its torsion portion and that portion coacting 85 with the faces of said lug.

7. A journal box comprising a lid, means hinging said lid to the journal box, a lug on the journal box having a plurality of faces serving to maintain the lid in a plurality of 90 positions, a torsion spring having spaced helixes and an intermediate extending loop portion therebetween adapted to coact with said faces, said helixes having extending ends coacting with the means hinging a lid to the journal box, and a member fulcrumed between said helixes, said member having a portion connected to the lid and another portion adapted to bear on the loop extension of said spring.

8. A journal box comprising a lid, means hinging said lid to said box, a lug on the journal box having a plurality of faces serving to maintain the lid in a plurality of positions, a torsion spring having spaced helixes and an intermediate loop portion adapted to coact with said faces, the opposite ends of said helixes being extended for coaction with the means hinging the lid to the journal box, and means connected with the lid and engaging said helixes for supporting the spring, said means having a portion positioned between the arms of the intermediate loop of said spring.

9. A journal box lid comprising a torsion spring provided with spaced helical portions and an extension adapted to coact with the usual hinge lug on an associated journal box having a plurality of faces and maintain the lid in a plurality of positions, another extension co-acting with means for hinging said lid to the box, and means connecting the spring to the lid, said latter means having oppositely extending portions embraced by said helical portions of the spring and forming bearings therefor.

10. In combination, a journal box provided with a hinge lug thereon, said lug having a plurality of faces, a lid, means hinging said lid to said box, a torsion spring comprising a 130

pair of oppositely wound helical portions and provided with an extension adapted to coact with the faces of the lug and another portion coacting with the hinging means for the lid, 5 and pivotal means extending in said helical portions for connecting said spring to the lid.

11. In combination, a journal box provided with a hinge lug having a plurality of faces, a pin extending through said lug, a lid, a torsion spring comprising spaced helical portions each formed of a plurality of loops and provided with an extension adapted to coact with the faces on the lug and another extension cooperating with said pin, and means 15 extending in said helical portions for connecting said spring to said lid.

12. In a journal box construction, the combination with a box proper; of a lid for closing said box; a spring bearing lug on said 20 box; means for pivotally connecting said lid to the box; and means for applying and substantially equally distributing a pulling force to the central portion of said lid, said means including a spring element disposed entirely 25 on the inner side of said lid, said spring having a portion thereof attached to the box proper, another portion thereof bearing on said lug, and another portion connected to the inner side of said lid.

13. In a journal box construction, the combination with a journal box proper; of a lid 30

hinged thereto; a spring disposed entirely between the lid and box, said spring having a portion thereof slidably connected to said lid on the inner side thereof to exert a pulling 35 force centrally of said lid, and another portion connected to the box proper.

14. In a journal box construction, the combination with a journal box proper; of a lid for closing said box; spring means for pulling 40 said lid to closed position; said means being movably connected to said lid and disposed entirely upon the inner side thereof, said means being connected to said lid for sliding movement relatively thereto during 45 movement of the lid; and means for equally distributing the force of the spring through an approximately fixed point on said lid, whereby the pressure on said lid around all 50 the edges thereof is in the same direction.

15. A journal box comprising a lid, a lug on said box having a plurality of faces serving to maintain the lid in a plurality of positions, a torsion spring provided with an extension coacting with said faces, and a lever 55 member having oppositely extending portions, one of which is movably connected to the lid, and another portion of which is adapted to bear upon the spring.

In testimony whereof I affix my signature.

PERCY R. DRENNING.
